PHOTOGRAPH PROCESSING DEVICE

Harry L. Stark, R.R. 1, North Webster, Ind.

Filed Sept. 15, 1960, Ser. No. 62,154

Term of patent 14 years

(Cl. D61—1)

Fig. 1.

Fig. 2.

Fig. 3.

Fig. 4.

FIG. 1 is a bottom view of my new photograph processing device, the opposite side thereof being plain;

FIG. 2 is a side view thereof;

FIG. 3 is an end view thereof; and

FIG. 4 is a view in perspective thereof.

The dominant feature of the design resides in the combination with a flat, rectangular sheet having rounded corners at one end and a rolled portion formed at the other end, of an inwardly folded portion formed at one end of the rolled portion, all as shown.

I claim:

The ornamental design for a photograph processing device as shown and described.
